INTERNAL COMBUSTION ENGINE

Balfour Read, Detroit, Mich.

Application February 23, 1939, Serial No. 257,779
In Great Britain February 24, 1938

5 Claims. (Cl. 123—75)

This invention relates to internal combustion engines and particularly such engines as operate upon the four stroke principle, the principal object being the provision of an engine of the type described of improved construction capable of operating in an improved and more economical manner.

Objects of the invention include the provision of a four cycle internal combustion engine having intake and exhaust valves and a pair of cam shafts for operating the same, together with means for varying the angular relationship of the cam shafts relative to the crankshaft of the engine; the provision of an improved construction for varying the angularity of the cam shaft in an engine of the type described; the provision of means in an engine of the type described for automatically varying the angular adjustment of the cam shaft in response to predetermined conditions of operation of the engine; the provision of an adjusting mechanism of the type described including pairs of intermediate driving gears for the cam shafts and means for simultaneously moving such pairs of intermediate gears about the axes of the driving and driven shafts, respectively, to alter the angular relationship of both cam shafts relative to the crankshaft or other driving shaft of the engine; the provision of an adjusting mechanism of the type described employing a chain as a driving medium between the cam shafts and the driving shaft together with bodily shiftable chain wheels or sprockets interposed between the driving shaft and each of the cam shafts and between the two cam shafts, respectively, together with means for simultaneously shifting the positions of the chain or sprocket wheels; and to provide an adjusting mechanism of the type described including automatically actuated hydraulic means the effects of which are controlled by the speed of rotation of the engine.

Other objects of the invention include means for effecting a satisfactory scavenging of the engine cylinders of a carburetor fed engine and particularly in an engine where the inlet valves and the exhaust valves therefor are controlled by separate cam shafts; the provision of an internal combustion engine having a pair of independent cam shafts each of which controls one inlet and one exhaust valve per cylinder; the provision of an internal combustion engine as above described in which means are provided for supplying air only to one of the inlet valves for each cylinder for scavenging purposes; the provision of means in connection with an internal combustion engine for overcoming the disadvantages appearing in

existing types and particularly the unsatisfactory performance of such engines in the lower speed ranges due to the falling off of the velocity of the combustible mixture particularly where large carburetors and mixture passages are employed; the provision of a construction as above described in which scavenging air is introduced into the cylinders of the engine and separate throttle means are provided for controlling the flow of scavenging air and the combustible mixture to the cylinders; and the provision of means automatically operable during operation of the engine for varying the proportional amounts of scavenging air and combustible mixture fed to the cylinders of the engine in accordance with certain operating conditions in the engine.

The above being among the objects of the present invention the same consists in certain novel features of construction and combinations of parts to be hereinafter described with reference to the accompanying drawings, and then claimed, having the above and other objects in view.

In the accompanying drawings which illustrate suitable embodiments of the present invention and in which like numerals refer to like parts throughout the several different views,

Fig. 1 is a partially broken, partially sectioned front elevational view of the front end of an internal combustion engine embodying one form of timing gear constructed in accordance with the invention;

Fig. 2 is a sectional view thereof taken mainly on the line 2—2 of Fig. 1;

Fig. 3 is a fragmentary plan view of the engine shown in the preceding figures showing the valves for one cylinder thereof;

Fig. 4 is a view similar to Fig. 1 but illustrating an alternative form of cam shaft drive;

Fig. 5 is a fragmentary transverse sectional elevational view of a known form of cylinder head which may be used in carrying out one feature of the invention;

Fig. 6 is a fragmentary sectional elevational view of a modified arrangement of the construction shown in Fig. 4 whereby the angular relationship of the two cam shafts relatively to the crankshaft can be adjusted automatically by hydraulic means;

Fig. 7 is a fragmentary, partially broken, partially sectioned view taken on the line 7—7 of Fig. 6;

Fig. 8 is a more or less diagrammatic, partially broken, partially sectioned end elevational view of a cylinder head, incorporating a pair of inlet valves, respectively, operable from the two adjust-

able cam shafts, arranged according to the invention, the view also showing a throttle valve, for the inlet valve by which air only is supplied, connected with a throttle valve by which the other inlet valve is supplied with carburetted mixtures; and,

Fig. 9 is a view similar to that in Fig. 8, showing an alternative arrangement according to the invention, in which throttle valves controlling the air passage and the mixture passage are interconnected, the former also being associated with means by which the angular relationship between the cam shafts and the crankshaft can be adjusted.

Fig. 10 is a more or less diagrammatic partially broken, partially sectioned and elevation of an engine combining the features brought out individually in Figs. 4 and 9.

This invention relates to internal combustion engines, particularly to such as operate on the four stroke cycle, of the kind having two cam shafts the angular relationship of both of which can be adjusted relatively to the crankshaft, the valve mechanism being such that by this angular adjustment, the overall inlet and/or exhaust period of each cycle can be increased or reduced.

Thus each cam shaft may control one inlet and one exhaust valve per cylinder, or instead of their being two inlet and exhaust valves per cylinder, there may be but a single inlet and a single exhaust valve, each of these being connected with the two cam shafts in such a manner that the overall inlet and exhaust period of each cycle can be increased or reduced. The present invention provides improved means for adjusting such cam shafts and particularly to such means as will be automatically operated in response to predetermined conditions of operation of the engine.

According to one feature of the invention, each cam shaft is driven through a pair of intermediate gears, both intermediate gear pairs being simultaneously movable about the axes of the driving and driven shafts, respectively, to alter the angular relationship of both cam shafts relatively to the crankshaft. Obviously, the driving shaft may be the crankshaft or some other shaft driven therefrom, and the driven shafts may be the cam shafts or other shafts from which the cam shafts are driven.

According to another feature of the invention, both cam shafts are driven by means of an endless chain embracing a driving chain wheel and two driven chain wheels, in combination with intermediate chain wheels disposed in such manner that two of them can be positively moved, while the third is automatically moved by a spring maintaining substantially constant tension in the chain, to alter the angular relationship of both cam shafts relatively to the crankshaft. The invention further includes an engine, of the kind specified, of which the angular relationship of the two cam shafts relatively to the crankshaft can be adjusted automatically by hydraulic means, dependently upon the engine speed.

The invention further embraces the combination with a carburetor fed internal combustion engine, of which each cam shaft controls one inlet and one exhaust valve per cylinder, of means for supplying air only to the inlet valve of a cylinder which opens first when the cam shafts have been angularly adjusted, with the object of scavenging a cylinder by air during the overlap period between the exhaust and inlet

periods. It is well known that conventional types of carburetor fed internal combustion engines, designed to give a high volumetric efficiency at high speeds, must be equipped with relatively large carburetors if full advantage is to be taken of their capabilities. Such carburetors, however, do not generally give very satisfactory performances in the lower speed ranges, due to the comparatively low velocity of the air flowing through them.

According to a further feature of the invention, the first opening inlet valve of a cylinder is supplied with air only through a throttle valve, the carburetted mixture to the other inlet valve being supplied through another throttle valve (or valves). By closing the air throttle valve to a greater extent than the other at low engine speeds, the velocity of the air flow through the carburetor can be increased. The throttle valves may be linked together or otherwise interconnected so that the air throttle valve will automatically throttle to a greater extent than the mixture throttle valve, as the latter is progressively closed from the wide open position.

The differential throttle action above mentioned may be automatically controlled in response to the adjustment of the angular relationship between the cam shafts and the crankshaft, as by means of the oil pressure of the engine. Thus, the adjusting means of the cam shafts, automatically controlled responsively to the engine speed, may be arranged to act on the first-mentioned throttle valve.

It should be understood that the principles of the cam shaft drives shown in the drawings may be used for the adjustment of cam shafts mounted in any position on an engine. For example, it is common practice to mount two cam shafts on the cylinder head of an overhead valve engine, and operate two or four valves by direct action. In cases of this kind, a single chain embracing both cam shaft chain wheel and a sprocket on the crankshaft may be impractical; and it may be necessary to mount the driving wheel for the cam shafts on a layshaft substantially above the crankshaft center, and to drive the layshaft from the crankshaft by an auxiliary chain or other suitable means. Such auxiliary chain can also be conveniently used for driving accessories. For similar reasons, it may be desirable to add auxiliary gears to the train shown in Fig. 1. However, where possible it will usually be desirable to mount the driving gear or wheel for the cam shafts on the engine crankshaft and it is shown in this position in the drawings by way of illustration. It is also obvious that a variety of means for changing the position of the shiftable gears or chain wheels may be employed, those shown in the drawings being illustrated only in the broader sense.

Referring now to the drawings and particularly to the construction shown in Figs. 1 to 3, 11 and 12 are cam shafts driven at half the speed of the crankshaft 13 by gears 14, 15, 16, 17, 18, 19 and 20. The cam shafts 11 and 12 revolve in the opposite direction to the crankshaft 13. The gears 15 and 18 are mounted in separate, pivotally mounted carriers 21 and 22, respectively, which are capable of partial rotation about the axis of the crankshaft 13. The gears 16 and 19 are mounted in carriers 23 and 24 which are capable of partial rotation about the centers of the cam shafts 11 and 12, respectively. The gears 15 and 16 are maintained

at the proper center distance by the links 25, and the gears 15 and 18 by the links 28. The movement of the gears 15 and 18 is controlled by the links 27 and 28 which may be operated by one of several methods to be later described.

When the centers of the gears 15 and 18 are moved to positions 15¹ and 18¹ (or to some intermediate positions) by movements of the links 27, 28 to the positions 27¹, 28¹ the cam shafts 11 and 12 are respectively advanced and retarded with relation to the crankshaft 13. Obviously the angular adjustment of each cam shaft may be made equal or otherwise, dependent upon the geometry and proportions of the gear train.

Each cylinder of the engine is provided with four conventional valves 30, 31, 32 and 33 (as shown by Fig. 3) actuated, respectively, by the rockers 34, 35, 36 and 37 from the cam shafts 11 and 12 through the medium of push rods 38 and tappets 39. The valves 30, 31, 32 and 33 include two intake valves and two exhaust valves and in the broader aspects of the invention these may be arranged as desired. In other words both exhaust valves may be located on one side of the engine and both intake valves on the other, or one inlet valve and one exhaust valve may be located on each side, but in any case each cam shaft must operate one exhaust valve and one inlet valve. As a matter of illustration it is assumed that 30 and 31 are exhaust valves, and 32 and 33 are inlet valves and the rocker arms are arranged accordingly. When the gears 15 and 18 are in the slow speed position shown, the exhaust cams 40 and 41 are preferably set to operate the exhaust valves 30 and 31 in unison. When, however, the gears 15 and 18 are moved respectively anti-clockwise and clockwise with reference to the crankshaft axis, the exhaust cam 40 on the cam shaft 11 opens the valve 30 earlier, and the exhaust cam 41 on the cam shaft 12 closes the valve 31 later, thus increasing the total opening period of the two valves by an amount equal to the total angular adjustment of the cam shafts 11 and 12 with respect to crankshaft 13.

In a similar manner, the inlet cams 42 and 43 on the cam shafts 11 and 12, respectively, may be set to operate the valves 32 and 33 in unison at slow speeds, and to open the valve 32 earlier and to close the valve 33 later as their respective cam shafts are advanced and retarded.

It will be understood that in the broader aspects of the present invention any suitable means may be provided for operating the links 27, 28 and, therefore, controlling the rotational positions of the cam shafts 11 and 12 with respect to the crankshaft 13. One such means is illustrated in Fig. 1 including a cylinder 63, suitably mounted on the engine frame, fitted with a piston or plunger 64 pivoted to a connecting rod 65 which in turn is connected to the upper and inner ends of the links 27 and 28. The closed end of the cylinder 63 is connected to a source of oil under pressure, which is responsive to the engine speed, through an orifice 66. At low engine speeds when the oil is warmed up (when the oil pressure is low,) the piston 64 is held at the top of its stroke by a suitable spring 67. As the engine speed increases the rising oil pressure forces the piston outwardly of or downwardly in the cylinder 63 against the action of the spring 67, thus causing shifting of the links 27 and 28 whereby as previously described, one cam shaft will be advanced and the other retarded.

In Figs. 4 and 10 the crankshaft 44 drives the cam shafts 45 and 46 in the same direction and at one-half crankshaft speed through the medium of a chain 47 and chain wheels 48, 49 and 50. Idler chain wheels 51, 52 and 53 are provided for the purpose of cam shaft adjustment, and to maintain correct tension in the chain. Assuming that the cam shafts 45 and 46 are in optimum relationship to the crankshaft 44 for slow speed performance, it is obvious that a movement of the center of the chain wheel 51 to a new position 51¹ will advance the cam shaft 45 and retard the cam shaft 46.

In order to support the chain wheels 52 and 53 for their required movement, they are mounted between the free ends of pairs of links 54 the opposite ends of which are pivotally secured to the engine frame as indicated. In the construction illustrated in Fig. 4 a piston 63', piston or plunger 64', piston rod 65', and spring 67' corresponding to the similarly numbered parts shown in Fig. 1 are employed but in this case the rod 65' is fixed with respect to the piston 64' and extends downwardly therefrom where its lower end is guided in a bearing member 70 fixed with respect to the engine frame at such point. Intermediate its length the rod 65' is provided with a fixed bracket 73 upon which the chain wheel 51 is rotatably mounted. A cross-bar 68 is also mounted upon the bracket 65 by means of a pin 71 located midway between the ends thereof. One end of the cross-bar 68 is connected by means of a link 72 with the journal for the chain wheel 53 supported between the free ends of the corresponding pair of links 54. The opposite end of the cross-bar 68 is connected to the journal for the chain wheel 52, carried between the free ends of the corresponding pair of links 54, by means of a coil spring 55.

In compression ignition and other engines in which the fuel is injected after the valves have closed, a duplication of inlet valves would be of no advantage so far as scavenging is concerned. For engines of this type, and in cases where the complication of multiple valves is not warranted, a method whereby the opening and closing points of an individual valve may be controlled by means of two cam shafts is shown by Fig. 5. Thus, both the cam shafts (of Fig. 1 or of Fig. 4) may be provided with an inlet and exhaust cam for each cylinder, together with tappets and push rods 60 and 61 for operating the rockers 57 and 58. One of the two similar valves is shown at 56, and each is provided with a rocker lever 59, which is preferably universally mounted on a hemispherical bearing 62, capable of sliding across the end of the valve stem, to accommodate the small lateral motion of the lever 59 which follows the movement of the end of the rocker 57. When the cam shafts have been advanced and retarded respectively from the slow speed position, the two cams which operate the valve 56 are out of phase. The rocker 57, for instance, will, therefore, depress the end of the lever 59 in contact with it, thus opening the valve 56 approximately one-half the amount, since the other rocker 58 forms a fulcrum for the lever 59. When the other rocker 58 depresses the end of the lever, both the rockers 57 and 58 cooperate in opening the valve 56. At the end of the opening period, the rocker 57 will come to rest first, and the closing point will be controlled by the rocker 58.

In carrying out the invention use may be made 75 of a standard pressure lubrication system having

the relief valve located in the pump itself. Such a relief valve is usually of the ball variety, but if it is of the plunger type coacting with a progressively opening orifice the pressure will be found to be nearly proportional to the speed after the oil has attained a fairly uniform temperature. The orifices 66 and 66' should preferably be quite small in order to prevent the adjustment from being carried out too actively when the oil is cold. On the other hand, if the relief valve is placed where shown in Fig. 6, the orifice 66'', corresponding to the orifices 66 and 66' previously described, should be at least as large as the effective opening of said relief valve. The representation in Fig. 6 is substantially the same in general as that in Fig. 4 and consequently like parts are indicated by the same numerals except that such numerals bear a double prime mark.

It is, of course, not necessary, in accordance with the invention, that the angular adjustment of the cam shafts should vary exactly proportionally with the engine speed throughout the whole range. In some cases it may be desirable that the ratio of the angular adjustment to the increase in speed should be different at slow and high speeds. It may even be desirable to make arrangements for the cam shaft adjustment to be reduced when the oil is cold.

Figs. 6 and 7 actually show a pressure-relief valve, of the progressively opening type, incorporated in the cylinder 63'', such relief valve including a pointed ended plunger 80 pressed in the closing direction by means of a spring 81 held in position by an adjustment nut 82.

In addition, a thermostatically controlled arrangement is introduced for taking care of the varying viscosity of the oil, as the hole 66'' cannot in these conditions be a small one. This is shown in Fig. 7 and includes a slidable valve member 83 controlled by a bi-metallic strip 84 shown in full lines in the position it occupies when the engine and oil are cold. In these conditions an opening 85 in the valve member is aligned with similar small openings 86 in the head of the cylinder 63''. As the oil reaches its normal running temperature the bi-metallic strip flexes (to the position shown by chain lines), and drawing with it the valve member progressively closes its passage.

If desired the spring 67'' opposing the movement of the plunger 64'' may be of the type having coils of a variable pitch in order to vary the timing characteristics.

Obviously other hydraulic means, the pressure of which varies with the engine speed, may be used instead of that specifically illustrated, and the thermostatic arrangement may be disposed elsewhere in the system. It will also be evident that the arrangement illustrated may be applied to the construction of Figs. 1 to 3, or to other types of engine to which the invention relates.

In Fig. 8, 88 and 89 represent the axes of the two cam shafts which can be angularly adjusted relatively to the crankshaft (not shown), as by the means shown in previous views. 90 and 91 are the two inlet valves for one cylinder of the engine, an inlet passage 92 for the former having a throttle valve 93 in it by means of which air alone can be supplied, whilst 94 is a throttle valve in the passage 95 by which carburetted mixture, from the carburetor 96, is conveyed to the inlet valve 91.

In the particular arrangement shown, which is by way of example only, one arm of a bell-

crank lever 97 is linked at 98 to an arm 99 fixed with respect to the mixture throttle valve 94, whilst the other arm is linked at 100 to an arm 101 fixed with respect to the air throttle valve 93. The full lines in the drawing show the position of the parts when the mixture throttle valve 94 is closed and the chain lines the position occupied thereby when the mixture throttle valve is fully open. The angular setting is such, it will be observed, that the air throttle valve 93 opens at a slower rate than the mixture throttle valve 94 during the initial opening of the latter, owing to the substantial alignment of the link 98 and arm 99 when the mixture throttle valve is closed.

Thus when the engine is idling, all the air for the engine passes through the carburetor. But at high engine speeds, when the cam shafts have been adjusted such that there will be an overlap between the air inlet valve and the exhaust valve, or that which opens last, the combustion space of the cylinder will be scavenged with air without there being any loss of combustible mixture.

In the construction of Figs. 9 and 10, the latter of which combines the constructions of Figs. 4 and 9 but in which the push rods and tappets are indicated by the same numerals as are employed in Fig. 2, and the cylinder valves by the same numerals as employed in Fig. 8, and which constructions are also given by way of example, there is indicated at 63' an hydraulic cylinder, corresponding to the cylinder 63'' shown in Fig. 4, by which the angular adjustment of the cam shafts relatively to the crankshaft can be automatically effected responsively to the engine speed as in the first described constructions. 110 represents an arm, with an arcuate slot in it, which is pivotally mounted at its lower end. Its upper end is linked at 111 to a bellcrank lever 112 linked at 113 to an arm 114 fixed with respect to the mixture throttle valve 115. Disposed in the arcuate slot is a pin 116 which is linked at 117 to a lever 118 connected to the cross-bar 68 operable by the piston of the hydraulic cylinder 63'. The pin 116 is also linked at 117a to a bellcrank lever 119 which is in turn linked at 120 to an arm 121 fast on the air throttle valve 122. It will be understood that the valves 122 and 115 and their corresponding passages 123 and 124, correspond to the valves 93 and 94, respectively, and passages 92 and 95, respectively, in Fig. 8.

Figs. 9 and 10 show in full lines the position of the parts when both throttle valves are closed and the cam shafts are adjusted for the idling speed of the engine. Opening the mixture throttle valve 115, while the engine is still idling, allows the arm 110 to swing idly about its pivotal mounting, as indicated by the chain lines, without the air throttle valve 122 being moved. Consequently, at this time all the air for the engine is being taken through the carburetor. Conversely, if the mixture throttle valve be fully closed, adjustment of the cross-bar 68 dependent upon the speed of the engine will serve for moving the pin 116 idly along the arcuate slot in the arm 110, as indicated by the chain lines. But if the cam shafts have been adjusted to any other position than that they occupy when the engine is idling, causing a corresponding rise of the pin 116 along the arcuate slot in the arm 110, then opening of the mixture throttle valve 115 will cause operation of the air throttle valve 122.

By means of the invention, it is possible at low engine speeds for the pure air to the one inlet valve of each cylinder to be throttled to a greater extent than the carburetted air, thus to increase the velocity of the air flow through the carburetor, and the arrangement may be such that, when the engine is running idle, all the air supply passes through the carburetor. As the engine speed increases the air throttle valve may be arranged to open progressively in relation to the mixture throttle valve so that at any desired speed between maximum and minimum both throttle valves will be open to the same degree.

Formal changes may be made in the specific embodiments of the invention described without departing from the spirit or substance of the broad invention, the scope of which is commensurate with the appended claims.

What I claim is:

1. In combination with an internal combustion engine having a cylinder provided with two inlet valves and two exhaust valves, a crankshaft, a pair of cam shafts, an operative connection between one of each of said pairs of valves with each of said cam shafts for operating said valves, one of said cam shafts being arranged to open and close the cooperating inlet valve in advance of the opening and closing of the remaining inlet valve by the remaining cam shaft during operation of said engine, means forming a driving connection between said cam shafts and said crankshaft for driving said cam shafts in timed relation with said crankshaft, shiftable elements associated with said driving connection operable to vary said timed relation whereby to enable the overall inlet and exhaust periods of each cycle of operation of said engine to be varied, means for shifting said shiftable elements during operation of said engine in response to variations of speed of said engine, a throttle valve associated with each of said inlet valves for controlling the feed of fluid thereto, means for feeding air only to the first mentioned inlet valves, means for feeding a carburetted mixture to said remaining inlet valve, and means interconnecting said throttle valves so constructed and arranged as to cause said throttle valve controlling the flow of air to one of said inlet valves to close in advance to closing of the throttle valve controlling

the flow of carburetted mixture to the other of said inlet valves during closing movements of both of said throttle valves.

2. The combination called for in claim 1 together with means operatively interconnecting said shifting means and said throttle valve for inter-related movements.
3. The combination called for in claim 1 in which said drive forming means comprises a sprocket wheel secured to each of said cam shafts and to said crankshaft, and a chain drivingly engaging all of said sprocket wheels, and said shiftable elements comprise a bodily shiftable sprocket wheel engaging said chain between each of the first mentioned sprocket wheels.
- 10 4. The combination called for in claim 1 in which said drive forming means comprises a sprocket wheel secured to each of said cam shafts and to said crankshaft, and a chain drivingly engaging all of said sprocket wheels, said shiftable elements comprise a bodily shiftable sprocket wheel engaging said chain between each of the first mentioned sprocket wheels, and said means for shifting said shiftable elements comprises a piston operatively interconnected with all of said bodily shiftable sprocket wheels, spring means constantly urging said piston in one direction, and means subjecting the opposite face of the piston to the pressure of the engine lubricating system.
- 15 5. The combination called for in claim 1 in which said drive forming means comprises a sprocket wheel secured to each of said cam shafts and to said crankshaft and a chain drivingly engaging all of said sprocket wheels, and said shiftable elements comprise a sprocket wheel engaging said chain between each of the first mentioned sprocket wheels, one of the last mentioned sprocket wheels being mounted for rectilinear movement and the remaining of the last mentioned sprocket wheels being mounted for bodily swingable movement, said one of said last mentioned sprocket wheels being positively connected to one of said remaining of said last mentioned sprocket wheels for movement simultaneously therewith and being connected to the other of said remaining of said last mentioned sprocket wheels by yieldable means.

BALFOUR READ.
